United States Patent Office.

A. C. JUDSON, OF GRAND RAPIDS, OHIO, ASSIGNOR TO HIMSELF
AND E. O. JUDSON, OF SAME PLACE.

Letters Patent No. 94,609, dated September 7, 1869.

IMPROVEMENT IN PLOWS.

The Schedule referred to in these Letters Patent and making part of the same.

To all whom it may concern:

Be it known that I, A. C. JUDSON, of Grand Rapids, in the county of Wood, and State of Ohio, have invented a new and useful Improvement in Plows; and I do hereby declare that the following is a full, clear, and exact description thereof, which will enable others skilled in the art to make and use the same, reference being had to the accompanying drawing, forming part of this specification.

This invention relates to improvements in plows, and has for its object to provide an improved construction of beam-wheel attachment and drawing-attachments.

Figure 1 represents a side elevation of my improved plow.

Figure 2 represents a plan view of the same.

Similar letters of reference indicate corresponding parts.

The landside A and mould-board B are made in two parts, to be joined at the front.

C represents a coulter, which is made of a flat plate of steel, properly shaped, as shown in the drawing, and placed between the front ends of the mould-board and landside previous to riveting. The rivets pass through all three of the parts, securing them firmly.

When the coulter becomes worn, it may be removed for grinding by punching out the rivets, and it is secured again as first stated.

I propose to make the plow-beam of two parts, D, bolted to the side of stock E at the rear, and connected behind the space for the wheel by a bolt, F, passing through a block, G, which maintains the parts the proper distance apart.

The said bolt is secured by a screw-nut, which may be unscrewed to permit the spreading of the parts, for adjusting the wheel H, which I propose to make as broad and large as can be conveniently done, for rolling easy and breaking down the stubble in advance of the plow.

This wheel I arrange in bearings in plates I, having a series of bearing-holes, for changing the journals, to vary the elevation of the beam for different depths of cutting.

Instead of the clevis commonly used, in order to place the wheel as close to the end as possible, or to use a short beam, I connect two perforated plates, K, to the beam, one on each side, and connect thereto a crotchet-clevis, L, straddling the front of the wheel.

This also is intended to be adjustable, and the adjustment is made by spreading the two parts of the beam apart, the same as for adjusting the wheel.

The coulter may, if preferred, have a bent shank, turning back and resting against the stock E, as represented in red at M.

Having thus described my invention,

What I claim as new, and desire to secure by Letters Patent, is—

The arrangement of the beam in two parts D, stock E, bolt F, block G, wheel H, draw-plates K, clevis L, and bearing-plates I, all substantially as specified.

A. C. JUDSON.
